(57) **CLAIM**

The ornamental design for a smoke detector, as shown and described.

DESCRIPTION

FIG. 1 is a first perspective view of a smoke detector showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the smoke detector thereof; and,

FIG. 10 is an enlarged view of the selected portion in FIG. 1.

The broken lines shown in the drawings depict portions of the smoke detector in which the design is embodied that form no part of the claimed design.
